UNITED STATES PATENT OFFICE.

WILLIAM H. BROWN, OF PHILADELPHIA, PENNSYLVANIA, ASSIGNOR TO ENERGY ELEVATOR COMPANY, OF PHILADELPHIA, PENNSYLVANIA, A CORPORATION OF PENNSYLVANIA.

HOISTING APPARATUS.

No. 820,764.

Specification of Letters Patent.

Patented May 15, 1906.

Application filed March 2, 1906. Serial No. 303,782.

To all whom it may concern:

Be it known that I, WILLIAM H. BROWN, a citizen of the United States, residing at the city of Philadelphia, in the county of Philadelphia and State of Pennsylvania, have invented certain new and useful Improvements 5 in Hoisting Apparatus, of which the following is a specification.

My invention has relation to a hoisting apparatus especially adapted for dumb-waiters in which the weight of the load to be lowered, as well as the upward movement of the load elevated, is utilized to actuate a brake to hold the same in any given position; and in such 15 connection it relates particularly to the constructive arrangement of the brake and hoisting mechanisms of the apparatus.

The principal objects of my invention are, first, to prevent a binding of the load-wheel 20 on its supporting-shaft by rigidly securing the same to the shaft of the hoisting apparatus and by separating the load-wheel from the mechanism controlling the rotation of the wheel and shaft; second, to so arrange the operating - wheel of the hoisting apparatus 25 loosely mounted on the shaft as to control the actuation of brake-arms, which automatically stop rotation of the load-wheel; third, to provide the shaft with a disk actuated by 30 the same which controls the brake-arms when the weight of the descending load or of an ascending load actuates the shaft, and, fourth, to provide the hoisting apparatus with a stationary ring or annulus and to surround 35 the same by the brake-arms, which when alternately controlled by the intervention of the operating-wheel and of the load-wheel are brought into and out of engagement with said ring or annulus to permit of the descent 40 or of the ascent of the dumb-waiter by the load-wheel.

The nature and scope of my present invention will be more fully understood from the following description, taken in connection 45 with the accompanying drawings, forming part hereof, in which—

Figure 1 is a view illustrating, partly in elevation and partly in section, a hoisting apparatus and also showing the manner of controlling 50 brake-arms by an operating-wheel mounted loosely on the shaft of the apparatus and by a disk fixed to the shaft controlled by the load-wheel rigidly secured thereto, all

embodimenting main features of my said invention; and Fig. 2 is a cross-sectional view on 55 the line xx of Fig. 1.

Referring to the drawings, a represents a shaft, which is supported at one end by a bearing a' and at its other end by the hub extension b' of an operating-wheel b , which extension in turn is supported by a bearing a'' . The bearings a' and a'' are supported by the beams a^3 of a structure (not shown) in which the dumb-waiter and a counterweight for the same are moved upward and downward and 60 are connected with each other by a rope (not shown) which passes over a load-wheel c , rigidly secured to the shaft a . This rope by its movements rotates the load-wheel c and shaft a . The dumb-waiter (not shown) being normally loaded, and thus overcoming 65 the action of the counterweight, (not shown,) tends to rotate the load-wheel c and by the same the shaft a in the direction indicated by the arrow in Fig. 1. This movement of the 70 shaft a by means of a disk d , rigidly secured thereto, serves to actuate a brake-lever f by the intervention of a bolt d' , connected with a disk d . This lever f by being lifted at its 75 free end brings two brake - arms g and g' , 80 pivotally connected in the points g^2 and g^3 to the other end of the same, in engagement with a ring or annulus h , preferably formed integral with the lower portion of the bearing a'' and connected therewith by extensions h' to stop 85 the rotation of the shaft a and load-wheel c and to prevent the dumb-waiter from falling.

As shown in full and dotted lines in Fig. 2, the brake-arms g and g' at one end, by means of a bolt i' , are directly connected with a 90 holder or plate i , loosely mounted on the shaft a and preferably of diamond shape in outline, while at their other end the arms g and g' are connected to the holder i by the intervention of the brake-lever f , which is pivotally secured thereto by a bolt i^2 , arranged intermediate of the pivotal points g^2 and g^3 of the brake-arms g and g' . Thus when the 95 brake-lever f is raised at its free end in Fig. 2 by the bolt d' , the same swinging with its 100 other end on the bolt i^2 , supported by the holder i , will draw the brake-arm g and g' toward each other and bring the same into engagement with the stationary ring h and clamp the brake - arms thereto, by which 105 clamping the further rotation of the shaft a

and load-wheel *c* is automatically stopped. In order to permit of a further rotation of the load-wheel *c* in the direction of the arrow indicated in Fig. 1 and descent of the dumb-waiter, the brake-arms *g* and *g'* must first be brought out of engagement with the ring *h*, which is accomplished by the following preferred mechanism: The hub extension *b'* of the operating-wheel *b* is provided with a flange *b*², between which and the disk *d* the brake-lever *f* is located.

When the operating-wheel *b* is rotated in the same direction as the load-wheel *c* by means of a rope passing over the same, its movement is transmitted to the flange *b*², which by means of a bolt *b*³ depresses the free end of the brake-lever *f*, and thus releases the brake-arms *g* and *g'* from the ring *h*, by which release the shaft *a* and load-wheel *c* will again be permitted to rotate in the direction indicated by the arrow. If, however, it becomes necessary to rotate the shaft *a* and load-wheel *c* in a direction opposite to that indicated by the arrow, so as to raise the dumb-waiter, (not shown,) this is accomplished by turning the operating-wheel *b* in the same direction—that is, opposite to that indicated by the arrow—by which movement the bolt *b*⁴ of the flange *b*² is brought into engagement with the brake-lever *f*, which by being depressed is brought into engagement with the bolts *d'* and *d*² of the disk *d*, secured to the shaft *a*.

By the depressing of the brake-lever *f* the brake-arms *g* and *g'* are brought out of engagement with the ring *h*, and at the same time the lever *f* by being brought into engagement with the bolts *d'* and *d*² permit the operating-wheel *b* by the intervention of the disk *d* to rotate the shaft *a* and load-wheel *c*, and thus to raise the dumb-waiter. As soon, however, as the operating-wheel *b* is not positively actuated the weight of the dumb-waiter rotating the shaft *a* will cause an instant application of the brake-arms *g* and *g'* to the ring *h* by raising the brake-lever *f*. Thus the load-wheel *c* and shaft *a* will be rotated as long as the operating-wheel *b* is positively actuated by an attendant either to raise or to lower the dumb-waiter, which tends to rotate the same in the direction indicated by the arrow.

If it is desired to normally rotate the shaft *a* and load-wheel *c* in an opposite direction to that indicated by the arrow by using a counterweight which is heavier than the dumb-waiter to permit the same to raise the waiter and overcome the weight of articles placed thereon, the brake-lever *f* in this instance is raised by the bolt *d*² of the disk *d*, by which movement the brake-arms *g* and *g'* will be brought into engagement with the ring *h*. Thus the ascent of the waiter is stopped until the lever *f* is again depressed by the bolt *b*⁴ of the flange *b*² of the operating-wheel *b*.

By using a heavier counterweight the attendant is relieved from raising the load carried by the dumb-waiter, which in this manner is lifted without exertion on the part of the attendant. This feature of the hoisting apparatus hereinbefore described is valuable in that it permits the attendant to rotate the operating-wheel *b* in the direction indicated by the arrow when the dumb-waiter is to be lowered, which movement of the rope actuating the operating-wheel *b* being in a downward direction requires, as is well known, a far less exertion on the part of the operator. A collar *k*, secured to the shaft *a*, tends to hold the operating-wheel *b* and its flange *b*² in proper position with respect to the ring *h*, while a collar *l*, secured to the shaft *a* and bearing against the holder *i* for the brake-arms *g* and *g'*, serves to hold the same and the lever *f* in proper position with respect to the ring *h*, disk *d*, and flange *b*² of the wheel *b*.

Instead of employing the hoisting apparatus for raising and lowering dumb-waiters, as hereinbefore described, it may be used with equally good results in raising and lowering any other type or kind of load or weight and of holding the same in any given position required.

Having thus described the nature and objects of my invention, what I claim as new, and desire to secure by Letters Patent, is—

1. A hoisting apparatus, comprising a shaft, a stationary ring surrounding said shaft, brake-arms surrounding said ring, a lever pivotally connected with said brake-arms, a load-wheel and a disk rigidly secured to said shaft, said disk arranged to actuate said lever and by the same bring said brake-arms into engagement with said ring to hold the load from either falling or rising when the same tends to rotate said shaft.

2. A hoisting apparatus, comprising a shaft, a stationary ring surrounding said shaft, brake-arms surrounding said ring, a lever pivotally connected with said brake-arms, a load-wheel and a disk rigidly secured to said shaft, and an operating-wheel loosely mounted on said shaft, said disk arranged to actuate said lever so as to bring said brake-arms into engagement with said ring to hold the load from either falling or rising when the same tends to rotate said shaft and said operating-wheel arranged to release said brake-arms from said ring by moving said lever in a direction opposite to that imparted to the same by said disk.

3. A hoisting apparatus, comprising a shaft, a stationary ring surrounding the same, brake-arms surrounding said ring, a load-wheel and a disk rigidly secured to said shaft, an operating-wheel loosely mounted on said shaft, a lever pivotally connected with said brake-arms and interposed between said disk and operating-wheel, said lever arranged to be independently actuated by said disk and

operating-wheel so as to bring said brake-arms into and out of engagement with said ring.

4. A hoisting apparatus, comprising a shaft, a stationary ring surrounding the same, brake-arms surrounding said ring, a load-wheel and a disk rigidly secured to said shaft, said disk having bolts, an operating-wheel having a flanged extension loosely mounted on said shaft, bolts, carried by said extension, a lever pivotally connected with said brake-arms and interposed between the bolts of said flanged extension and disk, said lever arranged to be independently and alternately actuated by the bolts of said disk and the flanged extension of said operating-wheel to bring said brake-arms into and out of engagement with said ring.

5. A hoisting apparatus comprising a shaft, a stationary ring surrounding the same, brake-arms surrounding said ring, a load-

wheel and a disk rigidly secured to said shaft, said disk having bolts, an operating-wheel having a flanged extension loosely mounted on said shaft, bolts carried by said extension, a lever pivotally connected with said brake-arms and interposed between the bolts of said flanged extension and disk, said lever arranged to be independently and alternately actuated by the bolts of said disk and the flanged extension of said operating-wheel to bring said brake-arms into and out of engagement with said ring and means loosely mounted on said shaft and adapted to support said brake-arms and lever.
